UNITED STATES PATENT OFFICE.

GEORGE R. LAYMAN, OF LINCOLN, ILLINOIS.

SAFETY DEVICE FOR ELEVATORS.

No. 834,816.

Specification of Letters Patent.

Patented Oct. 30, 1906.

Original application filed July 8, 1905, Serial No. 268,792. Divided and this application filed September 20, 1905. Serial No. 279,315.

To all whom it may concern:

Be it known that I, GEORGE R. LAYMAN, a citizen of the United States, residing at Lincoln, in the county of Logan and State of Illinois, have invented certain Improvements in Safety Devices for Elevators, of which the following is a specification.

This invention relates to elevators, and more especially to the class of safety devices for elevators, and the present application is a division of the application for patent which was filed by me on July 8, 1905, bearing Serial No. 268,792.

The present invention consists, therefore, in the particular construction and arrangement of the safety devices, all as hereinafter fully described, and particularly set forth in the appended claims.

In the accompanying drawings, which form a part of this specification, Figure 1 is a front elevation of an elevator embodying my improvements in safety devices, showing the parts thereof in their normal position during the travel of the elevator in the shaft. Fig. 2 is an enlarged transverse sectional view to more clearly show the engaging cams or dogs which are adapted to support the car or cage under certain conditions. Fig. 3 is a similar view to more clearly illustrate the operating means for throwing the cams or dogs against the uprights of the elevator-shaft. Fig. 4 is a detail view to show the particular construction of the cams or dogs and the manner of supporting the same.

Like letters of reference indicate like parts in all the views of the drawings.

It will be noted that I have illustrated my invention as applied to an elevator of the class employed in mines; but it will be obvious that the devices are readily applicable to other types of elevators comprising a car and uprights, the latter being constructed of wood.

In the present instance the car or cage comprises the upper horizontal parallel beams A A, spaced apart by means of a rectangular casting a and connected by the vertical plates B B to the bottom of the car or cage, such plates being extended, as at b, to form a connection for the hoisting and lowering means. This connection in the present instance comprises a plate C, to which the connecting-chains c are attached and to which is also attached the hoisting and lowering cable C', the latter being by way of the usual eyebolt c' and interposed compression-spring c'.

To provide for the attachment of my safety devices, hereinafter described, the plate C carries a second plate c³, suspended therefrom by means of the rods c⁴.

The car or cage travels between the uprights S, forming the elevator-shaft, as is usual, and said uprights are made of wood.

Supported beneath the parallel beams A A in brackets a' and a² are shafts D, and mounted upon these shafts between the aforesaid brackets a' and a² are cams or dogs E, the latter being disposed so as to travel with the car or cage at either side of the uprights S of the elevator-shaft. These cams or dogs are fixed to the shafts so as to turn therewith and are adapted to be thrown into engagement with the uprights, and thereby arrest the downward movement of the car or cage under certain conditions. The cams or dogs E are each provided with three engaging members, as e, e', and e², the engaging member e being slightly in advance of the others and is bifurcated to provide separate sharp teeth e² e², while said other members present straight edges and are stouter to thereby provide a stronger engagement after the aforesaid teeth have entered the upright. This construction of cam or dog insures a positive and secure engagement with the upright and prevents slipping, thereby providing for a quick stoppage of the car or cage.

The shafts D are provided with arms d, by which they are connected to a transverse bar F, having the upturned slightly-yielding end members f, and said bar is connected at its center to a vertical operating-rod G, which passes upward therefrom through a guide-plate a⁴, located between the beams A A, and is connected by a chain H to the plate c³ of the hoisting and lowering connections, hereinbefore described. A spring h is interposed between the chain and rod, and the connection is such that when the weight of the car or cage is on the cable C' the rod G will draw the bar F up snugly against the shafts D to thereby throw and maintain the dogs or cams out of possible engagement with the uprights S. In this position of the devices, therefore, they will not interfere with the usual running of the car. On the other hand, when the car or cage is released or not supported by the cable from any cause—for instance, by the breaking of the cable—the slack in the connections c C will permit the rod G and bar F to drop by gravity, and the latter being connected by the shafts D to the

cams or dogs will operate to throw the latter into engagement with the uprights, and thereby prevent the car or cage from dropping in the shaft. As stated, this operation 5 may be caused by gravitation of the rod and bar; but in order to strongly force the cams or dogs into engagement with the uprights, and thereby compel the teeth to firmly engage the latter, a strong helical spring I is mounted on the operating-rod G and interposed between the guide-plate a^4 and the aforesaid bar F, the tendency of which spring is to more positively operate said bar, as aforesaid.

15 It will be noted that the cams or dogs E are located between the brackets a^1 and a^2 , in which the shaft D has a bearing, and this provides a strong connection to withstand the strain when said cams or dogs are thrown 20 against the uprights and engage the same, thereby insuring that the car will be arrested and supported until the cams or dogs are disengaged. As a further reinforcement at this point the rock-shaft D may extend into 25 the plate B, as shown in Fig. 4 of the drawings.

The upturned end members f of the metal bar F will yield sufficiently to permit of the required movement of the arms d in throwing the cams into operative position, inasmuch as only a slight movement of said members is required and the spring I is strong enough for the purpose.

30 The operation of the improved safety devices will be readily apparent from the foregoing, and it will be seen that I provide a very simple arrangement that will be quickly thrown into operation automatically should an accident happen to the hoisting and lowering mechanism, which would relieve the car of the support of the cable. Also that the operation under such conditions is quick, positive, and effective. Furthermore, by providing the pull-cord n, which is attached 40 to the cross-bar F, the latter may be operated manually at any time to throw the cams into engagement with the uprights for the purpose of stopping the descent of the car, this operation being provided for by having 45 the spring h as a part of the connection between said bar and the hoisting and lowering cable. This manual operation of the safety devices may be necessary under certain conditions—for instance, should the attendant

on the car notice anything wrong and desire 55 to promptly stop the descent of the car or keep the cams in positive engagement with the uprights during its ascent.

Having thus described my invention, what I claim as new, and desire to secure by Letters Patent, is—

1. In a safety device for elevators, the combination with the car, hoisting and lowering cable, and uprights of the elevator-shaft, of rock-shafts carried by the car and disposed at opposite sides of the uprights of the elevator-shaft, cams or dogs fixed to said rock-shafts and adapted to engage the uprights at opposite sides thereof, a bar extending across the under side of the rock-shafts 70 and having upturned yielding members, arms connecting the rock-shafts to said yielding members, an operating-rod connected to the bar, a chain connecting said operating-rod to the hoisting and lowering cable, a compression-spring forming a part of the aforesaid chain connection, and a spring interposed between the bar and a fixed support on the car, together with a pull-cord connected to the aforesaid bar for manually operating the 80 rock-shafts, substantially as shown and for the purposes set forth.

2. In a safety device for elevators, the combination with the car, hoisting and lowering cable and uprights of the elevator-shaft, of rock-shafts carried by the car and disposed at opposite sides of the uprights, cams or dogs fixed to said rock-shafts and adapted to engage the uprights, said cams each having three members one in advance 85 of the others, the advanced member being bifurcated to provide a pair of sharp teeth which will enter the upright in advance of the other members, means connected to the hoisting and lowering cable for holding the 90 cams or dogs away from the uprights, and a spring connected to said means and adapted to throw the cams or dogs in engagement with the uprights when such connection is released, substantially as shown and described.

In testimony whereof I have signed my name to this specification in the presence of two subscribing witnesses.

GEORGE R. LAYMAN.
